UNITED STATES PATENT OFFICE.

CHARLIE R. STEEDMAN AND JOHN M. HUGHES, OF DENVER, COLORADO.

SNOW AND ICE MELTING VEHICLE.

950,413.

Specification of Letters Patent. Patented Feb. 22, 1910.

Application filed January 28, 1909. Serial No. 474,870.

To all whom it may concern:

Be it known that we, CHARLIE R. STEEDMAN and JOHN M. HUGHES, citizens of the United States, residing in the city and county of Denver and State of Colorado, have invented certain new and useful Improvements in Snow and Ice Melting Vehicles; and we do declare the following to be a full, clear, and exact description of the invention, such as will enable others skilled in the art to which it appertains to make and use the same, reference being had to the accompanying drawings, and to the figures of reference marked thereon, which form a part of this specification.

Our invention relates to improvements in vehicles adapted for use in melting snow and ice, being more especially intended for use in cleaning snow and ice from the streets in cities, though its use is evidently not limited to any particular location, since it may be employed to advantage wherever there is occasion for the performance of work of this character.

It is well known that it is customary in cities to remove the snow from the streets by shoveling it into wagons and hauling the same away to a distance where it is dumped. This is a very laborious and expensive proceeding, and our object is to provide an apparatus adapted to do away with the necessity for hauling the snow and ice away, in order to get rid of it, and to this end we make provision in our improved vehicle for melting the snow and ice as fast as it is shoveled thereinto, whereby it is converted into water and either kept in a tank and discharged into the sewer after the tank has been filled to the limit of its capacity; or, if the weather permits, the water may be allowed to run out of the tank as fast as the snow and ice melt, and pass into the gutter, and thence into the storm sewer. When, however, the weather is so cold as to make this impracticable, the water may be retained until a considerable quantity has accumulated, when the vehicle may be driven to an opening communicating with the storm sewer, when the water may be quickly discharged thereinto.

In our improved apparatus, burners are arranged underneath the vehicle body, into which the snow to be melted is shoveled, the construction being such that the heat of these burners acts directly upon the vehicle body, which is, of course, composed of metal,

whereby the snow and ice may be melted practically as fast as they are shoveled thereinto. In other words, a combustion chamber is arranged below the bottom of the vehicle body, and through this chamber are passed burners or perforated pipes to which fuel oil may be fed for the purposes of combustion. In order to facilitate the melting of the snow, the bottom of the vehicle body, or that in direct communication with the combustion chamber, is corrugated, thus greatly increasing the heating surface.

Heretofore, so far as we are aware, no vehicle has been equipped with means for directly applying heat to the body or receptacle into which the snow is discharged, though provision has been made for heating water upon a vehicle and discharging the hot water upon the snow within the vehicle body. This, however, is entirely distinct from our invention, since the heat of our combustion chamber is applied directly to the vehicle body for melting the snow therein.

Having briefly outlined our improved construction, we will proceed to describe the same in detail, reference being made to the accompanying drawing, in which is illustrated an embodiment thereof.

In this drawing, Figure 1 is a vertical longitudinal section of a vehicle, equipped with our improvement. Fig. 2 is a cross section of the same taken on the line 2—2, Fig. 1. Fig. 3 is a top plan view of our improved snow and ice melting vehicle.

The same reference characters indicate the same parts in all the views.

Let the numeral 5 designate the framework of the vehicle, which is shown in the drawing as mounted upon wheels 6. It is evident that our improved vehicle may be equipped with any desired means of locomotion, since, if it is more convenient, runners instead of wheels may be employed without departing from the spirit of the invention as defined by the appended claims. In this application the term vehicle is used in a broad and comprehensive sense, not being limited to conveyances provided with wheels.

Upon the framework 5 of the vehicle is mounted a tank 7 for receiving the water 8, into which the snow and ice have been converted. This tank is equipped with a rearwardly located, depended discharge pipe 9, controlled by a valve 10. By back-

ing the vehicle to the manhole of a storm sewer, the contents of the tank may be quickly discharged into the sewer by opening the valve 10.

5 Mounted above the tank, and adjacent to the top thereof, is a combustion chamber 12, through which are passed transverse bars 3, forming a support for the snow receptacle or vehicle body 13, whose bottom 10 is formed of relatively deep corrugations, whereby the surface exposed to the action of the heat of the combustion chamber is made comparatively extensive, thus making it practicable to greatly facilitate the melting 15 of the contents of the receptacle 13.

Passed longitudinally through the combustion chamber 12, and at the base or bottom of the receptacle 13, are perforated pipes 14, constituting oil burners, the said 20 pipes being in communication with a fuel oil tank 15, from which leads a pipe 16 to a transversely arranged conduit 17, with which all of the pipes 14 are in communication. Each of these pipes 14 is equipped, 25 close to the conduit 17, with a controlling valve 18.

Mounted upon the oil tank 15 is an air pump 19, whose cylinder 20 is in communication with the interior of the tank, whereby any desired pressure upon the oil therein may be maintained. This pump may be operated through the medium of a lever 21, fulcrumed at 22, and connected at 23 with a piston stem 24 of the pump. The person 30 in charge of the vehicle may subject the liquid fuel therein to the necessary pressure by operating the pump whenever the pressure gage 25, with which the tank is equipped, indicates that more pressure is 35 desirable.

40 The combustion chamber 12 is closed in front by a plate 26, which is notched or recessed to fit the corrugated bottom of the vehicle body 13. This plate gives a 45 port to the said bottom, and makes it practicable to make it of relatively thin material, whereby the heat may quickly act upon the contents of the receptacle. This combustion chamber is entirely closed, except at 50 the rear, where there is a draft opening 27, controlled by a gate or damper 28.

Forward of the plate 26, the chamber of the body 13 extends to the top of the tank 7, where the latter is provided with an opening 55 29, covered by a screen 30. The water into which the snow is converted, passes into the tank 7 through this opening. By virtue of the screen any foreign matter therein is prevented from entering the tank, 60 and possibly clogging the discharge pipe. Any impurities, as indicated at 30, may be removed by opening a door 31, which is hinged to the body 13, as shown at 32.

65 From the foregoing description the use of our improved apparatus will be readily un-

derstood. Assuming that the fuel oil is turned into the perforated pipes 14 under the necessary pressure, and the oil lighted within the combustion chamber of the vehicle, it is evident that the corrugated bottom of the receptacle 13 will soon become heated. In the use of the vehicle it may be driven along the street or wherever the snow and ice to be removed are located, the latter being shoveled thereinto, whereby it is brought in contact with the hot corrugated bottom of the receptacle and quickly melted. The bottom of this receptacle is downwardly inclined from its rear extremity, whereby the water passes immediately to the forward 80 extremity of the receptacle, and thence through the opening 29 into the tank 7. If desired, this water may be allowed to accumulate until the tank 7 is filled, when the water may be discharged into the sewer, as 85 heretofore explained; or, if deemed practicable, the valve 10 may be left open, allowing the water to run out upon the street and pass automatically into the sewer.

By virtue of the fact that the top of the 90 water tank 7 forces the bottom of the combustion chamber, the heat from the latter serves to prevent the freezing of the water within the tank 7 in cold weather. This is an important feature, where the temperature 95 is sufficiently low to freeze water under ordinary circumstances.

Having thus described our invention, what we claim is:

1. A vehicle of the class described, including a snow and ice receptacle, a water tank underneath said receptacle and a screen covered opening forming a connection between them, a combustion chamber located between the bottom of the receptacle and the top of 105 the water tank, and means located in the combustion chamber for heating the latter to the desired degree for snow melting purposes, substantially as described.

2. A vehicle of the class described, including a water tank, a receptacle mounted on the water tank, having a corrugated bottom a closed space being left between the tank and the receptacle, forming a combustion chamber, perforated pipes located in the 115 combustion chamber, between the pockets formed by the corrugated bottom of said receptacle and a source of fuel oil mounted on the vehicle, and with which the said pipes are connected.

3. A vehicle of the class described, including a receptacle, having a corrugated bottom, a combustion chamber adjacent to the said bottom, perforated pipes located within the combustion chamber, a liquid-fuel-containing tank mounted on the vehicle, means connected with the tank for placing the liquid fuel under the necessary pressure, and a connection between the said tank and the 125 perforated pipes in the combustion chamber 130.

to allow the liquid fuel to pass to the said pipes, the combustion chamber being closed at the bottom, and provided with a regulated draft opening, substantially as described.

cation with the latter, which is provided with a screen-covered opening for the purpose, a space being left between the top of the tank and the bottom of the receptacle, forming a combustion chamber, perforated 25 pipes located within the combustion chamber, an oil tank mounted upon the vehicle, a connection between the said tank and the pipes within the combustion chamber, and means for regulating the pressure upon the 30 liquid fuel within the tank, substantially as described.

In testimony whereof we affix our signatures in presence of two witnesses.

CHARLIE R. STEDMAN.
JOHN M. HUGHES.

Witnesses:

JESSIE F. HOBART,
A. EBERT O'BRIEN.

4. A vehicle of the class described, provided with a water tank, a receptacle located above the tank, and having its bottom downwardly inclined toward one extremity, a screen covered opening forming a communication between said receptacle and tank, the apparatus having a combustion chamber interposed between the bottom of the receptacle and the top of the tank, and means for supplying the combustion chamber with 15 the necessary fuel for combustion purposes, substantially as described.

5. A vehicle of the class described, including a water tank, having a valve controlled outlet, a receptacle mounted above the tank, 20 and whose forward portion is in communication with the latter, which is provided with a screen-covered opening for the purpose, a space being left between the top of the tank and the bottom of the receptacle, forming a combustion chamber, perforated pipes located within the combustion chamber, an oil tank mounted upon the vehicle, a connection between the said tank and the pipes within the combustion chamber, and means for regulating the pressure upon the liquid fuel within the tank, substantially as described.
